UNITED STATES PATENT OFFICE.

WILHELM GRIESSE, OF ST. LOUIS, MISSOURI.

BEER-FAUCET.

1,156,774.

Specification of Letters Patent. Patented Oct. 12, 1915.

Application filed December 12, 1912. Serial No. 736,410.

To all whom it may concern:

Be it known that I, WILHELM GRIESSE, a citizen of the United States, residing at St. Louis, in the State of Missouri, have invented new and useful Improvements in Beer-Faucets, of which the following is a specification.

This invention has reference to faucets, and, in particular, to the faucets used in brewing systems for discharging the contents of the cooling, storage and other tanks comprehended in such systems.

It proposes, in brief, certain hereinafter described improvements in or relating to the valve and valve-operating means of a faucet of the type specified.

An embodiment of the invention is illustrated in the accompanying drawing, whereof:

Figure 1 is a vertical sectional view, showing the attachment and mounting of the improved faucet; Fig. 2 is a horizontal section taken on the line 2—2 of Fig. 1; and Fig. 3 is a detail perspective view of one of the elements included in the valve-operating means.

In said drawings, 1 designates, generally, the bottom portion of the afore-mentioned tank, which may be of any desired construction and is incased or embedded in a concrete wall or covering 2, the concrete also covering the protecting casing of the valve and its operating means.

In the bottom wall of the tank, there is formed an opening 3 wherein is fitted the upper end of a vertical sleeve 4 that constitutes one of the parts of the said protective casing, the sleeve end being preferably provided with an out-turned beveled flange 5 that is held from turning in its seat by means of spurs, or similar pointed projections 6. The lower portion of this sleeve is externally threaded and carries a suitable clamping nut 7 and an interposed washer 8, these parts coöperating with the flange 5 to clamp the sleeve firmly in place. Within said sleeve is fitted a vertical pipe 9 which is in threaded engagement therewith at its upper end, the relative positions of the sleeve and pipe being fixed through the agency of cooperating abutting shoulders 10 and 11 provided thereon. Pipe 9 terminates at its upper end substantially coincident with sleeve 4 but its lower end projects beyond that of the said sleeve into a hollow horizontal cylinder 12 which is closed

at its rear end and constitutes the other part or element of the protective casing, the upper portion of this cylinder having an opening 13 through which the pipe 9 extends and in which the lower end of sleeve 4 is fitted. At its lower end, pipe 9 is provided with a forwardly-extending lateral branch or elbow 14 in which is fitted the rear end of a pipe 15 that projects through a central opening in the plate 16 at the front end of the cylinder, the said cylinder end lying flush with the outer face of the concrete wall 2 and having plate 16 removably connected to it in any desired manner. The front end of pipe 15, in turn, is reduced and exteriorly threaded and is connected by a cap-nut 17, or the like, to a downwardly-curved nozzle 18.

The valve, which controls the passage of the beer or other liquid through the pipes 9 and 15 and the nozzle 18, is here shown as in the form of a plate or disk 19 that fits in a seat 20 formed by beveling the upper end face or edge of pipe 9, and is connected, integrally or otherwise, to a depending axial stem or valve rod 21. The valve and valve stem or rod are arranged for vertical movement, and the said stem is centered and guided during its movements by means of a fixed spider 22, through whose perforated hub the stem slides, the valve being normally held in closed position through the agency of a downwardly-acting spring 23 that bears at opposite ends against the spider hub and the upper of a pair of nuts 24 fitted upon the threaded portion of the stem.

To raise the valve against the action of its controlling spring, for the purpose of opening communication between the tank and faucet, there is provided a device which preferably consists, as shown, of a rocker 25 that engages the lower end of the valve stem, and a push-rod 26 that is connected with said rocker and serves to effect the working movement thereof. The rocker is fulcrumed in a bearing seat 27 formed in the bottom of pipe 9, at the junction of its vertical and horizontal arms, and is here shown as comprising a pair of vertical wings 28, arranged in spaced parallel relation, and a base 29 which connects the lower edges of said wings and is thickened and rounded at its rear end to form the fulcrum. These wings have a somewhat triangular shape, and their apices are directed for-

wardly and are formed with alining openings for the reception of the ends of a cross-pin 30. On said pin is loosely mounted a sleeve 31 formed with a lateral arm 32 that 5 projects forwardly into engagement with the socketed head 33 provided on the rear end of the horizontal push-rod 26, this rod being slidably mounted in the hubs of a pair of spiders 34 and 35, fixed in the ends 10 of pipe 15, and a perforated boss 36 provided on the nozzle 18 in line with said hubs. The hub of the spider 34 is enlarged and extended rearwardly, thus forming a socket or cap 37 which receives the rod head 33 and serves to limit the outward movement of the push-rod. At its outer end, the push-rod carries a button, or similar finger-piece or handle 38. Inward movement of the push-rod 26 will, therefore, effect an upward and rearward swinging movement of 20 rocker 25, with the obvious result that the valve stem, which normally rests at its lower end upon the base of the rocker, will be raised, carrying the valve 19 with it and 25 thus opening communication between the faucet and the tank. When the pressure upon the push-rod is removed, the several parts will be automatically returned to their respective initial positions, through the 30 agency of the spring 23.

It will be seen that the lower end of the valve rod or stem 21 is in movable engagement with the base 29 of the rocker 25 or said valve rod simply has a contacting bearing 35 on the base of the rocker and as the latter is operated through the medium of the push rod 26 the upper surface of the base with which the lower end of the stem or rod 21 has engagement practically operates as a cam surface on which the lower 40 end of said stem or rod has movement. By this means the valve stem or rod 21 is always maintained in true vertical position. Moreover, the lateral arm 32 of the sleeve 31 has only contacting engagement with the 45 socket of the head 33 and as a consequence the connection or operating means between the push rod 26 and valve stem or rod 21 is unattached to either the push rod or valve 50 rod and both of the latter parts operate without the least deflection from their normal positions, thereby reducing wear on the bearings or supporting spiders for the push rod and valve rod and also dispensing with 55 the connecting pivots or other attaching means, which will be of material advantage in the assemblage of the several parts of the faucet. It will also be seen that all the operating parts of the faucet are inclosed 60 mainly within the pipe 9 and its lateral branch or elbow 14 and the pipe 15, and the only exteriorly projecting portion of the valve mechanism is the operating extremity of the push rod 26 and its finger piece, handle or pressure head 38. More-

over, the pipe 9 with its lateral branch or elbow 14 and the pipe 15 are mainly inclosed within the sleeve 4 and the cylinder 12 and the said pipes and the valve mechanism therein are thus very fully protected. 70

I claim:

1. In a faucet of the class specified, the combination of a pair of pipes connected end to end at right angles, the one pipe being provided with a nozzle at its free end, 75 a valve seated in the free end of the other pipe and having an axial stem depending through the interior of the said pipe, an operating rod slidably mounted in the interior of the pipe having the nozzle and projecting 80 exteriorly of the said nozzle, and means disposed wholly within the pipes adjacent to the juncture of the latter and loosely engaged by the end of the valve rod and of the push rod, the valve rod being provided 85 with means for restoring all of the parts to normal position when released.

2. In a faucet, the combination of a vertical pipe, a valve seated in the upper end of said pipe and provided with a depending operating rod arranged in the interior thereof, a horizontal pipe connected at its lower end to the lower end of the vertical pipe and provided at its outer end with a nozzle, a 90 slideable push rod axially mounted within said horizontal pipe and projecting through the nozzle for operation, and a rocking means interposed between the inner adjacent ends of the valve rod and push rod and with which the latter rods have loose 95 contacting engagement, the rocking means being wholly inclosed within a portion of the vertical pipe.

3. In a faucet, the combination of a vertical and a horizontal pipe connected end to end at right angles, the horizontal pipe being provided with a nozzle, a valve seated in the free end of the vertical pipe and having an axial rod depending through and arranged wholly within the vertical pipe, a 100 rocker wholly inclosed within the pipes at the junction thereof and having one portion loosely bearing and fulcruming upon the lower portion of the vertical pipe and provided with a base on which the lower end 105 of the valve rod has unattached contacting bearing, and a push rod mounted in the horizontal pipe and having the inner end portion thereof also loosely engaging a part 110 of the rocker, the valve rod being provided 115 with means for restoring all of the parts to normal position when released.

4. In a faucet, the combination of vertical and horizontal pipes connected end to end at right angles, the horizontal pipe being provided with a nozzle at its free end, a valve seated in the free end of the vertical pipe and having an axial rod arranged wholly within and depending through the 120 interior of the vertical pipe, a rocker mount- 125

ed within and wholly inclosed by the said pipes at the junction thereof and having a rounded extremity loosely bearing and fulcruming upon the lower portion of the vertical pipe and also provided with a base on which the lower end of the valve rod has loose contacting bearing, an arm pivotally connected to the upper portion of the rocker, an operating rod slidably mounted in the interior of the horizontal pipe and projecting exteriorly through the nozzle and also having at its inner end a socketed head wherein the arm of the rocker loosely projects and bears upon said head for swinging the rocker inwardly to elevate the valve rod and open the valve, and means engaging the valve rod for restoring all of the parts to normal position when the operating rod is released.

5. In a faucet, the combination of a vertical pipe provided at its upper end with a valve, a horizontal pipe connected at its lower end to the lower end of the vertical pipe and provided at its outer end with a nozzle, a valve rod depending from the

valve at the upper end of the vertical pipe 25 and located wholly interiorly of the latter pipe, an operating push rod extending through the horizontal pipe to the vertical pipe and having its outer extremity projecting through the nozzle, means in the lower 30 portion of the vertical pipe and wholly inclosed by the latter and engaged by the lower end of the valve rod and the inner extremity of the operating push rod whereby the push rod is caused to elevate the valve rod and 35 open the valve, the said means being loosely disposed in the lower portion of the vertical pipe, and means on the valve rod for restoring the parts to normal position when the push rod is released.

40 In testimony whereof I have hereunto set my hand in presence of two subscribing witnesses.

WILHELM GRIESSE.
